UNITED STATES PATENT OFFICE.

WALTER EVERETT MOLINS, OF LONDON, ENGLAND.

DEVICE FOR TAKING SHEETS FROM A STACK OF PAPER OR THE LIKE.

1,382,213.

Specification of Letters Patent. Patented June 21, 1921.

Application filed February 2, 1921. Serial No. 441,897.

To all whom it may concern:

Be it known that I, WALTER EVERETT MOLINS, a citizen of the United States of America, residing in London, England, have 5 invented certain new and useful Improvements in Devices for Taking Sheets from a Stack of Paper or the like, of which the following is a specification.

The present invention has for its object 10 an oscillating suction or other device for taking sheets from a stack of paper, the invention residing in the fact that the pivot on which the device is mounted is connected with a supporting device located beneath 15 the stack of sheets of paper and is mounted in such a manner that the upper edge of the support is arranged approximately in line with the center of the pivot on which the sheet taking device oscillates, the said pivot 20 being arranged in an adjustable holder. In correspondence with the thickness of the sheet of paper to be removed from the stack, the discharge slot for the sheets at the bottom of the receptacle containing the stack 25 of paper is rendered wider or narrower by shifting the support forward or rearward. Thus, for example, in the case of a thick sheet of cardboard which is difficult to bend, the support is adjusted more to the rear, 30 thus rendering the slot wider and allowing greater length for bending than would be the case with thin sheets of paper. The suction or like device acts on the most forward portion of the sheet of paper to be removed 35 from the stack. If the position of the support is modified, the sheet-removing or suction device must also be adjusted to a position as near as possible to the edge of the sheet, as otherwise when the sheet of thick 40 paper is bent downward by the device, it would have a tendency to become detached from the latter. In the case of large displacements of the support the sheet-removing device would be moved too far to the 45 rear for it to be effective. The present invention overcomes this difficulty.

The invention is illustrated by way of example in the accompanying drawings, in 50 which Figures 1 and 2 represent the device in side elevation, and Fig. 3 is a front elevation partly in section.

The bottom of the receptacle 1 for the reception of the stack of sheets of paper comprises a discharge aperture for the sheets 55 and beneath this aperture a roller 2 is arranged to support the portion of the stack

which rests over the slot. The spindles of the roller 2 are mounted in a bearing 4 connected with a bearing 5 in which the pivot 6, on which the sheet-taking device oscillates, 60 is mounted. The pivot 6 is engaged in a slot guide 7 rigidly connected with a tube 8 upon which the sheet-removing fingers 9 are arranged. By means of a cap nut arranged on the pivot the slot guide 7 can be pressed 65 toward the inner portion of the bearing arranged in the bearing 5, so that the slot guide 7 with the sheet-removing device can be shifted on the pivot 6 after the nut has been slackened and retained in the desired 70 position by tightening the nut. The supporting roller 2 is mounted in such a manner that the upper edge of this roller is located as far as possible in line with the axis of the pivot 6. The bearing 5 is connected 75 with an adjustably mounted supporting arm 10.

The operation of the device is as follows:—If thick sheets are to be removed from the stack, the roller 2 must be correspondingly adjusted. The point of attack 80 of the sheet-removing device should remain unaltered as far as possible, however, and in order to attain this result (Fig. 2) the arm 10 is suitably adjusted and with it the 85 bearing 5 and the roller 2 connected therewith. The cap nut is then tightened so that the device cannot shift upon the rotatable pivot. Buckling of the sheet of paper which would otherwise take place when it is bent 90 downward by the sheet-removing device, is prevented as the support and the pivot on which the device oscillates are both displaced while the sheet-taking device itself may remain in the same relative position in 95 respect of the pile.

Having thus described the nature of the 100 invention and the best means I know of carrying the same into practical effect, I claim:—

1. An oscillating device for taking sheets of paper or the like from a stack, characterized by the fact that the pivot on which the device oscillates is connected with a support located beneath the stack of paper and is 105 mounted in such a manner that the upper edge of the support is arranged approximately in line with the axis of the pivot for the device, this pivot being arranged in an adjustably mounted holder.

2. A device in accordance with claim 1, characterized by the fact that the pivot on 110

which the sheet-taking device oscillates is adapted to be displaced with reference to the latter and locked in a guide slot provided for that purpose which is connected with 5 said sheet-taking device.

3. In a sheet removing device having a receptacle for a stack of sheets provided with an aperture in its bottom, the combination with a supporting arm adjustable as 10 regards the aperture, a pivot on said arm, a rocking member depending from said pivot and having a guide-slot engaging said pivot,

clamping means on said pivot for rigidly holding said guide-slot in an adjusted position on said pivot, a plurality of sheet removing fingers on said rocking member and a roller for supporting the stack of sheets mounted in a bearing on said arm in such a manner that its upper edge is in approximate alinement with the axis of said pivot. 15

In testimony whereof I have signed my name to this specification. 20

WALTER EVERETT MOLINS.
